CLAIM

The ornamental design for a drum bucket, as shown and described.

DESCRIPTION

FIG. 1 is a top perspective view of the drum bucket, showing the new design;

FIG. 2 is a bottom perspective view of the drum bucket thereof;

FIG. 3 is a front view of the drum bucket thereof;

FIG. 4 is a rear view of the drum bucket thereof;

FIG. 5 is a left side view of the drum bucket thereof;

FIG. 6 is a right side view of the drum bucket thereof;

FIG. 7 is a top view of the drum bucket thereof; and,

FIG. 8 is a bottom view of the drum bucket thereof.

The broken lines represent the portions of the drum bucket that form no part of the claimed design.
